UNITED STATES PATENT OFFICE

100,165

DESIGN FOR A DINING TABLE

William Kalpakoff, Southgate, Calif.

Application May 13, 1936, Serial No. 62,618

Term of patent 3½ years

To all whom it may concern:

Be it known that I, William Kalpakoff, a citizen of the United States, residing at Southgate, in the county of Los Angeles and State of California, have invented a new, original, and ornamental Design for a Dining Table, of which the following is a specification, reference being had to the accompanying drawing forming part thereof, the drawing presenting a perspective view of the table showing my design.

The table is characterized by having a pedestal type leg at each end. Each pedestal leg has a

receded base. The upper part of the pedestal leg has vertical flutings on all sides with plane surfaces on each side of the series of vertical flutings and the receded base has horizontal flutings on all sides. In addition, on the end face of each pedestal leg there are vertical handles for opening and closing a door.

I claim:

The ornamental design for a dining table as shown and described.

WILLIAM KALPAKOFF.
